130,958

DESIGN FOR AN EMBROIDERED TEXTILE FABRIC OR SIMILAR ARTICLE

Adolphe Dreyfus, Mount Vernon, N. Y., assignor to Sol Wolfman, Inc., New York, N. Y., a corporation of New York

Application November 24, 1941, Serial No. 104,275

Term of patent 3½ years

To all whom it may concern:

Be it known that I, Adolphe Dreyfus, a citizen of the United States, residing at Mount Vernon, Westchester County, and State of New York, have invented a new, original, and ornamental Design for an Embroidered Textile Fabric or Similar Article, of which the following is a specification, reference being had to the accompanying drawing, forming part thereof, wherein the figure is a plan view of a piece of embroidered textile fabric, showing my new design, the same being depicted on a dark background for the purpose of bringing out more clearly the details of the design.

I claim:

The ornamental design for an embroidered textile fabric or similar article, substantially as shown and described.

ADOLPHE DREYFUS.
